UNITED STATES PATENT OFFICE

OSCAR M. ANDERSON AND FRED W. JUENGST, OF NEW BRITAIN, CONNECTICUT, ASSIGNORS TO LANDERS, FRARY & CLARK, OF NEW BRITAIN, CONNECTICUT, A CORPORATION OF CONNECTICUT

DESIGN FOR AN ELECTRIC TOASTER

Application filed April 30, 1932. Serial No. 43,681. Term of patent 14 years.

To all whom it may concern:

Be it known that we, OSCAR M. ANDERSON, a subject of the King of Sweden, and FRED W. JUENGST, a citizen of the United States, both residing at New Britain, in the county of Hartford, State of Connecticut, have invented a new, original, and ornamental Design for an Electric Toaster, of which the following is a specification, reference being had to the accompanying drawing, forming part hereof;

In said drawing:

The figure is a perspective view of an electric toaster showing our design.

We claim:

The ornamental design for an electric toaster as shown.

OSCAR M. ANDERSON.
FRED W. JUENGST.
